(57) **CLAIM**

The ornamental design for a foot massage device, as shown and described.

DESCRIPTION

FIG. 1 is a top plan view of a foot massage device showing my new design;

FIG. 2 is a bottom plan view thereof;

FIG. 3 is a left side view thereof;

FIG. 4 is a right side view thereof;

FIG. 5 is a rear view thereof;

FIG. 6 is a front view thereof; and,

FIG. 7 is a perspective view thereof.

The broken lines shown in the drawings are for the purpose of illustrating portions of the foot massage device, which form no part of the claimed design.
